WARDROBE TRAY

Joseph H. Plotkin, Chicago, Ill., assignor to S. Dresner & Son, Inc., Chicago, Ill., a corporation of Illinois

Application August 1, 1938, Serial No. 222,396

2 Claims. (Cl. 190—41)

My present invention relates to a tray, applicable to hand luggage, and equipped with wardrobe fixtures of improved character. More particularly, the present invention is directed to the mounting for the wardrobe fixtures within the tray, and the manner in which such mounting cooperates therewith to reinforce the tray structure, and to provide for the ready accommodation of garments which are to be folded and packed in such a tray which is receivable within a luggage case of appropriate character. The parts which enter into the construction, hereinafter to be described, are simple, inexpensive, easily assembled, and may be operated without liability of breakage. A suggestive embodiment of this invention is set forth in the accompanying drawings, wherein:

Figure 1 is a perspective view of a luggage case with its cover opened up to exhibit the wardrobe tray, the clothes supporting rack being shown as swung to an upper or vertical position;

Figs. 2, 3, 4 and 5 are perspective views illustrating successive stages in the folding and packing of garments within the wardrobe tray;

Fig. 6 is a top plan view of the tray;

Fig. 7 is an enlarged detail in vertical section, taken on line 7—7 of Fig. 6;

Fig. 8 is a similar view, taken on line 8—8 of Fig. 7;

Fig. 9 is a similar view, taken on line 9—9 of Fig. 7;

Fig. 10, which is a view similar to Fig. 9, shows the rack in the position it occupies after being slid and swung to an upper position; and

Fig. 11 is a detail in section showing one of the forward rack corners.

The wardrobe tray of my invention is shown in connection with a luggage case having a body B to which is hinged a cover C. Within the case body is affixed a suitable support (see Fig. 1) on which the tray T may be rested, desirably in an elevated position above its bottom. The case may be equipped with the usual carrying handle 12 and latches 13 by which it is maintained reasonably in locked condition.

The tray comprises a bottom 15, end walls 16, a back wall 17 and, if desired, a low front wall 18. As by means of an appropriate fabric, the tray is desirably covered over its bottom and marginal walls to present a neat and attractive appearance. The several tray walls are joined to the bottom and to each other where they meet, and in addition I provide between each end and back wall a fixture F constituting an internal

reinforcing angle plate which will now be described.

Referring particularly to Fig. 8, each of these two fixtures is in the form of an angle plate having end flanges 20 and 21, in right angular relation, adapted to rest against the inner faces of adjacent walls of the tray for connection therewith as by rivets 22; between these flanges the fitting is reversely bent to provide walls 23 and 24 at right angles to each other and each spaced from and parallel with one of the tray walls. The walls forming each fixture are desirably extended for substantially the full vertical height of the tray, and at the upper end one wall is laterally bent to provide a cover 25 which overlies the space which is closed in by the fixture. Formed in the fixture side 24 which is parallel with one tray end wall is a slot 26 (see Fig. 9) extending vertically thereof from a point close to the bottom clear to the top and then laterally at 27 part way across the cover. The slot thus provided in one fixture lies opposite the corresponding slot in the other fixture.

A wardrobe rack R is formed to lie within the tray. This may be of the open or closed type of construction, as preferred. In the suggestive construction illustrated in Fig. 6 this rack comprises three bars, the two end ones 30 of which extend parallel with the tray ends, being spaced from each other a distance substantially the length of the remaining bar 31 which lies proximate to the front wall 18 of the tray. The cross sectional form of each bar, best shown in Figs. 9 and 11, is concavo-convex with inturned flanges 32 which provide in effect a channel. Connection is made between each end bar and the forward bar as by means of a rounded corner piece 33, also of concavo-convex form, with its two ends terminating in arms 34 which extend in right angular relation for interfitting within the end of the channeled bar proximate thereto. When so arranged, the corner pieces may be locked to the bars as by means of rivets 35, spot welds, or the like. The bars thus connected constitute three outer margins of the rack, and are transversely braced as by a longitudinal bar 36, a cross bar 37, and other obliquely extending bars 38, these several bars, at points of crossing, being joined to others as by spot welds. The effect of such a structure is to provide an open rack that is light, amply strong for its intended purposes, and rounded outwardly on each of its three sides over which clothes are to be draped in the manner presently to be described.

The rack is provided with a pair of oppositely extended trunnions disposed adjacent the rear end thereof. As shown best in Fig. 10, each trunnion may comprise a spool 40 which is fitted 5 upon and locked to a pin 41 extending through an end bar of the rack from the proximate end of the brace bar which is joined thereto. The base *a* of the spool (see Fig. 9) is rounded in conformity with the convex face of the bar against 10 which it is fitted, whereby to prevent rotation relative thereto. The outer flange *b* of the spool which forms the head of the trunnion is flattened in the plane of the rack so that when the rack is vertically positioned the width of the trunnion 15 head is such that it may enter through the slot 27 in the cover of the reinforcing fixture. When swung to any other position, however, the trunnion width is in excess of that of the slot.

I have secured to the back wall of the tray a 20 base 45 on which is supported a U-shaped hook which comprises an upwardly extending post 46 in spaced relation to the base. A hanger *H* which is adapted for reception within the tray beneath the rack is equipped with a clip 47 adapted to fit over the post whereby the hanger is connected slidably thereto. A hook 48, pivotally secured to the hanger as at 49, is provided at one end with a lateral finger 50 adapted, in the 25 position shown in Fig. 6, to engage the post beneath a pin 51 provided near its upper end whereby the hanger is prevented from sliding off the post except when the hook is laterally turned to a position which withdraws the finger away from the post.

In use, the rack may be positioned vertically, 30 as in Figs. 1 and 2, where it is attachable to or removable from the tray fixture. One or more pair of trousers may then be laid in the tray, as suggested in Fig. 2, and a coat and vest, which is 35 draped over a hanger, may then be laid over the trousers whose ends up to that point are extended outwardly beyond the case ends, as shown in Fig. 3. With the hanger positioned on the post the rack is then swung down to a position 40 within the tray so as to overlie the garments which have already been positioned therein. As 45 a final operation the trouser ends may be folded in over the rack (see Fig. 4), and the lower portion of the coat and vest be folded over the trouser ends, as shown in Fig. 5. The rack trunnions may slide upwardly as required by the 50 thickness of the clothing which lies therebelow. Two or more suits may be accommodated within the tray, depending upon its depth, additional 55 hangers being used as needed.

The tray, together with the draped garments therein, may be lifted from the case in its entirety whenever it is desired to have access to its other contents. Also, whenever desired, the 60 clothing draped over the rack may be extended outwardly again, permitting the freed rack to be swung upwardly, whereupon the topmost hanger with garments thereon may be lifted from the tray without disturbing the clothing therebelow. 65 The rack may also be entirely removed from the

tray, but only after it is swung to a substantially vertical position wherein the heads of its trunnions are free to pass through the slots in the covers of the two reinforcing fixtures.

I claim:

1. A luggage tray including end walls and a back wall, corner fittings each secured to an end wall and the back wall and rigidly connecting the same and each having an intermediate portion spaced from said end wall in opposed relation, each fitting being also provided with a top covering the space between said intermediate portion and the adjacent end wall, and each fitting being also provided with a slot of substantially uniform width throughout its length extending through said top and through said intermediate portion and downwardly thereon and terminating short of the bottom of the fitting, and a garment supporting rack receivable within the tray and provided with oppositely extending trunnions 10 operating in said slots, each trunnion having a flattened terminal head received in the aforesaid space, said heads being of greater length than the width of the slots and having a thickness less than the width of said slots, the length of the 15 head extending transversely of said slot in the housed position of the rack and extending longitudinally of said slot in the unhoused position of said rack to permit the head to pass through the slot in the top of the fitting when the rack 20 is swung out of the tray to a remote position with the transverse head disposed longitudinally of the slot.

2. A luggage tray including end walls and a back wall, corner fittings each secured to an end 25 wall and the back wall and rigidly connecting the same and each having an intermediate portion spaced from said end wall in opposed relation, and each fitting being also provided with a vertical slot open at its top and of substantially uniform width throughout its length extending 30 downwardly through said intermediate portion and terminating short of the bottom of the fitting, a garment supporting rack receivable within the tray and provided with oppositely extending trunnions 35 swingingly and slidably operating in said slots, each trunnion having a flattened terminal head received in the aforesaid space, said heads being of greater length than the width of the slots and having a thickness less than the 40 width of said slots, the length of the head extending transversely of said slot in the housed position of the rack and extending longitudinally of said slot in the unhoused position of said rack to permit the head to pass through the slot in the fitting when the rack is swung out of the 45 tray to a remote position with the transverse head disposed longitudinally of the slot, and means on the fitting disposed adjacent the upper end of the slot close to one of the edges thereof 50 adapted to engage the head to prevent movement thereof out from the slot except when the head is aligned longitudinally of the slot.

JOSEPH H. PLOTKIN.
